UNITED STATES PATENT OFFICE

HATTIE HON AND HOWARD H. SHUMAKER, OF MEMPHIS, TENNESSEE

ATTACHMENT FOR PIANO KEYBOARDS

Application filed July 30, 1931. Serial No. 554,134.

For the sake of illustration it might be stated that it is absolutely necessary in teaching pupils the art of pianoforte playing, to stress the importance of the proper positioning of the hands and wrists of the pupils over the keyboard, to insure the striking of the keys by the ends of the fingers, to accomplish a variance of tone qualities.

It is therefore the primary object of the present invention, to provide a guard or hand builder, to be attached to the keyboard of a pianoforte, in such a way that a person playing the piano equipped with the device will be compelled to hold his hands in the proper

way, while striking the keys.

An important object of the invention is to provide a device of this character which may be readily and easily positioned on the usual keyboard of a pianoforte, eliminating the necessity of making alterations in the keyboard construction in any way, to mount the device.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a fragmental plan view of the keyboard of a pianoforte, showing a device constructed in accordance with the invention as positioned thereon.

Figure 2 is a front elevational view thereof.

Figure 3 is a sectional view of the device as mounted on a keyboard.

Figure 4 is an end elevational view of the device.

Referring to the drawings in detail, the keyboard of a pianoforte is indicated generally by the reference character 5 to which the device forming the subject matter of the invention, is secured.

The guard or hand builder comprises end members 6 which are substantially triangu-

lar in formation, the lower ends thereof, however, being provided with cut out portions defining shoulders 7, so that the end members may be slid into position over the white keys of the keyboard of a pianoforte, with the extension 8 formed by the cut out portions resting on the ledge 9 directly in front of the keys. The end members 6 are also formed with horizontally disposed parallel grooves 10, which grooves provide guides for the ends of the length of glass indicated at 11 which acts as a guard for the knuckles of the hands of the player to prevent the knuckles from being raised too high.

Thus it will be seen that by adjusting the length of glass 11, the height that the hands may be raised may be regulated to meet various requirements.

Connecting the end members 6, is a rod 12, that has right angled ends 13 formed with eyes 14 at their ends, which eyes accommodate the pins 15. Adjusting pins 16 extend laterally from the end members 6 and engage the ends 13 providing supports for the rod 12 so that the rod 12 may be held in various positions of adjustment.

While the rod 12 provides means for connecting the end members 6, it is pointed out that it also provides a guard under which the hands of the operator are positioned, to prevent the hands from being raised too high. Extending inwardly from the end members, at points directly above the keys, are pins 17, over which the hands are positioned, when using the device.

A metallic plate indicated by the reference character 20 also connects the end members 6 to hold them in proper spaced relation with each other, the plate 20 being of a width to completely cover the inner edges of the end members, as clearly shown by Figure 3 of the drawings.

The reference character 18 designates arms that are secured to the outer surfaces of the end members 6, the arms being provided with hooks 19 disposed at their free ends, so that they may be hooked over the inner ends of the black keys of the keyboard of the pianoforte, thereby securing the device in position.

From the foregoing it will be obvious that

a pupil in placing his hands within the hand builder in a manner as described, will be compelled to bend the knuckles and wrist in such a way as to insure a striking of the keys with the ends of the fingers thereby insuring a variance of tone quality.

Having thus described the invention, what is claimed is:

1. A device of the class described, comprising end members, said end members adapted to be positioned on the keys of a pianoforte, a horizontal translucent member mounted on the end members and under which the hands of the player are positioned, a rod extending across the front of the device in spaced relation therewith, and under which the hands are positioned, pins extending inwardly from the end members in parallel relation with the rod, and over which the hands of the operator are positioned, and means for removably securing the device to the keyboard.

2. A device of the class described, comprising end members, said end members adapted to be positioned on the keys of a pianoforte, means for connecting the end members, a transparent member adjustably mounted on the end members and under which the hands of the player are positioned to restrict upward movement of the hands of the operator, a rod extending forwardly from the device and disposed parallel with respect to the keyboard, pins extending inwardly from the end members and over which the hands of the operator are positioned, and means for securing the device to the keyboard of a pianoforte.

3. A device of the class described, comprising end members, means for connecting the end members to hold the end members in proper spaced relation with each other, a rod having inwardly extended ends connected to the end members, said rod being disposed in spaced relation with the keys of the keyboard, means for adjusting the rod vertically, pins extending inwardly from the end members and over which the hands of the player are positioned, and means for securing the device to the keys of the keyboard.

4. A device of the class described, comprising end members, said end members adapted to be positioned on the keys of a pianoforte, a rod extending forwardly from the keyboard and in spaced relation therewith, means for connecting the rod to the end members, pins extending inwardly from the end members and over which the hands of the player are positioned, an adjustable transparent member mounted on the end members and adapted to prevent the hands of the player from being raised too high, and means for securing the device to the keys of the keyboard.

5. A device of the class described, comprising

end members, adapted to be positioned on the keys of a keyboard of a pianoforte, a rod connected with the end members and extending forwardly in parallel spaced relation with the keyboard of a pianoforte, guard members supported by the end members for restricting the movements of the hands of the player, arms extending inwardly from the end members, hook members in the inner ends of the arms, and said hook members adapted to engage behind certain of the keys of the keyboard, to hold the device in position.

In testimony that we claim the foregoing as our own, we have hereto affixed our signatures.

HATTIE HON.
HOWARD H. SHUMAKER.
